ALARM

George Kratz, Jamaica, N. Y.

Application April 1, 1937, Serial No. 134,390

5 Claims. (Cl. 179—5)

This invention appertains to new and useful improvements in alarms and more particularly to an annunciator for warning automatically over a telephone line the occurrence of a robbery or burglary being committed.

The principal object of the present invention is to provide an apparatus which can be started by the mere pushing of a button and which will annunciate from a phonograph over a telephone line the occurrence of some illegal act, thus make it unnecessary that the person starting the same make any suspicious move that might draw the suspicion of the wrong doer.

Another important object of the invention is to provide an apparatus of the character stated which will be substantially automatic in operation and not susceptible to the ready development of defects.

Other important objects and advantages of the invention will become apparent to the reader of the following specification.

In the drawings:—

Figure 1 represents a vertical sectional view through the housing of the apparatus.

Figure 2 represents a top plan view of the apparatus with the top removed.

Figure 3 is a diagrammatic view disclosing the electrical connection between the electrical devices involved.

Referring to the drawings wherein like numerals designate like parts, it can be seen that the apparatus consists of the housing 5 mounted on the base 6. This housing has a hinged closure 7 at its front side. The top 8 of the housing is situated a slight distance downwardly from the upper edges of the side, back and front walls and to the upper edge of the back wall is hingedly secured the cover 9.

To the top 8 is secured the motor 10 for driving the turntable 11 upon which a record 12 is placed.

Numerals 13 represents the pick-up arm suitably mounted to the sound arm 14 which, in turn, is swivelly connected to the upper end of the horn 15. Numeral 16 represents a telephone transmitter having the usual receiver hook 17. This telephone instrument is set upon the base 6 in the cabinet and is preferably secured in place against shifting.

A post 18 is secured to the top of the housing top 8 and is provided with a laterally disposed arm 19 at its upper end. This arm and the post 18 are of current conducting material, the arm 19 having a cut out portion in which an insert of insulation 20 is placed. Furthermore, the arm

19 is of arcuate shape, the same being on an arc having the same center as the swingable sound arm 14, and against this arm 19 rides the spring brush 21 carried by the arcuate conduit 22 projecting laterally from the sound arm 14.

Projecting laterally from the turntable 11 is the hook 23 which engages the upstanding lug 24 on the bellcrank 25. The bellcrank 25 carrying the contact 26 which is engageable with the contact 27. At the opposite end of the bellcrank 25 from the lug 24, attaches the cable 28 which is trained over the pulley 29 and downwardly through the opening 30 in the top 8. On the base 6 is the pulley 31 under which the cable 28 is disposed and this cable also extends under the second pulley 32 on the base 6 and then upwardly to connect to the receiver hook 17.

As can be seen in Figure 3, a plurality of switches 33 are connected in series with the conductor 34 from the post 18 and the conductor 35 to the motor 10. A jumper around the switches 33 has the contact 27 and bellcrank 25 installed therein. The conductor 22 from the brush 21 extends to the opposite side of the motor 10.

It can now be seen, that normally the apparatus is set in the position shown in Figure 2. A momentary closing of any one of the switches 33 will close the circuit A (see Figure 3) energizing the motor 10. A slight movement of the turntable 11 is sufficient to release the bellcrank 25, thus permitting the receiver hook 17 to rise and establishing the telephone line for communication thereon. Immediately sound from the rotating record will be delivered by the horn 15 to the transmitter 16 and the alarm message of the record 12 will be transmitted.

When the record has been completely played, the brush 21 will have reached to the insulation insert 20 and this will break the electric circuit, thus deenergizing the motor 10.

It will also be observed, that the closing of the switches 33 need only be momentary because as soon as the bellcrank 25 is released the circuit 10 is established around the switches 33 by way of the jumper B.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. In combination, a phonograph including a

- turntable, a motor for driving the turntable, an electric circuit including the motor and a manual switch for initially controlling operation thereof, a shunt circuit around the said switch,
- 5 a turntable operated switch in the said shunt circuit for closing the shunt circuit upon operation of the turntable for subsequently controlling operation of the motor, a telephone instrument including a transmitter and receiver hook, said
- 10 transmitter being in sound receiving relation with the phonograph, and means between the turntable and the receiver hook for releasing the receiver hook upon operation of the turntable.
2. In combination, a phonograph including a turntable, a motor for driving the turntable, an electric circuit including the motor and a manual switch for initially controlling operation thereof, a shunt circuit around the said switch, a turntable operated switch in the said shunt circuit
- 15 for closing the shunt circuit upon operation of the turntable for subsequently controlling operation of the motor, a telephone instrument including a transmitter and receiver hook, said transmitter being in sound receiving relation with the phonograph, and means between the turntable and the receiver hook for releasing the receiver hook upon operation of the turntable, said last mentioned means including the switch of the shunt circuit.
- 20 3. In combination, a phonograph including a turntable, a motor for driving the turntable, an electric circuit including the motor and a manual switch for initially controlling operation thereof, a shunt circuit around the said switch,
- 25 a turntable operated switch in the said shunt circuit for closing the shunt circuit upon operation of the turntable for subsequently controlling operation of the motor, a telephone instrument including a transmitter and receiver hook, said
- 30 transmitter being in sound receiving relation with the phonograph, and means between the turntable and the receiver hook for releasing the receiver hook upon operation of the turntable, said last mentioned means consisting of a pro-
- 35 jection on the turntable, a rockable member
- 40 adapted to be engaged by the turntable and held
- 45

in said position, a connection between the rocker and the receiver hook for holding the receiver hook in circuit closed position when the rocker is engaged by the turntable projection.

4. In combination, a phonograph including a turntable, a motor for driving the turntable, an electric circuit including the motor and a manual switch for initially controlling operation thereof, a shunt circuit around the said switch, a turntable operated switch in the said shunt circuit for closing the shunt circuit upon operation of the turntable for subsequently controlling operation of the motor, a telephone instrument including a transmitter and receiver hook, said transmitter being in sound receiving relation with the phonograph, and means between the turntable and the receiver hook for releasing the receiver hook upon operation of the turntable, said last mentioned means consisting of a projection on the turntable, a rockable member adapted to be engaged by the turntable and held in said position, a connection between the rocker and the receiver hook for holding the receiver hook in circuit closed position when the rocker is engaged by the turntable projection, said switch for closing the shunt circuit including a contact on the rocker and a second contact in the path of the contact on the rocker.

5. In combination, a phonograph including a turntable, a motor for driving the turntable, an electric circuit including the motor and a manual switch for initially controlling operation thereof, a shunt circuit around the said switch, a turntable operated switch in the said shunt circuit for closing the shunt circuit upon operation of the turntable for subsequently controlling operation of the motor, a telephone instrument including a transmitter and receiver hook, said transmitter being in sound receiver relation with the phonograph, and means between the turntable and the receiver hook for releasing the receiver hook upon operation of the turntable, and means for breaking the said motor circuit when the record has been played.
